COVERED COOKING POT

Masaru Yamazaki, 188 Ozu-machi, Hiroshima, Japan

Filed Nov. 30, 1964, Ser. No. 32,838

Term of patent 14 years

(Cl. D44—1)

FIG. 1 is a top plan view of a covered cooking pot showing my new design;

FIG. 2 is an exploded side elevational view;

FIG. 3 is a side elevational view rotated 90° from the position of FIGURE 2; and

FIG. 4 is a bottom plan view.

I claim:

The ornamental design for a covered cooking pot, as shown.
